UNITED STATES PATENT OFFICE.

HENRY NOEL POTTER, OF NEW ROCHELLE, NEW YORK, ASSIGNOR TO GEO. WESTINGHOUSE, OF PITTSBURG, PENNSYLVANIA.

ELECTRIC FURNACE WITH MAGNETICALLY-ROTATED CHARGE.

975,571.

Specification of Letters Patent. Patented Nov. 15, 1910.

original application filed July 25, 1904, Serial No. 217,954. Divided and this application filed July 1, 1905.
Serial No. 267,914.

To all whom it may concern:

Be it known that I, HENRY NOEL POTTER, a citizen of the United States, and resident of New Rochelle, county of Westchester, 5 State of New York, have invented certain new and useful Improvements in Electric Furnaces with Magnetically-Rotated Charges, of which the following is a specification.

10 In certain electric furnace operations it is desirable to stir a bath of fluid metal while it is maintained at a very high degree of temperature. Ordinarily mechanical stirring processes cannot readily be practiced under such conditions of operation and it becomes necessary to resort to other means for accomplishing the stirring of the fluid. I propose to impress upon the mass of fluid metal the effects of a rotating magnetic field, making the fluid the closed secondary of an induction motor. Under these circumstances a rotation or revolution of the fluid will be caused and this revolution of the fluid can be effected in one direction or 15 the other by an appropriate manipulation of the electric currents producing the rotary field. The stirring action can be assisted by giving to the vessel which contains the fused metal an irregular configuration either on 20 the bottom or sides or both, so that the general rotation of the mass will be accompanied by eddies which assist in stirring the fluid. The idea is applicable either to a resistance furnace where the melted metal 25 is itself the resistance or to furnaces either of the arc or resistance type in which the melted metal is heated from a source exterior to itself. The molten metal may fill 30 a circular trough, or it may lie on a base in the general form of a disk; or it may constitute an annulus surrounding the lower carbon of an arc furnace, in which the carbons are coaxial and vertical.

The present invention is of wide application, inasmuch as most of the materials produced in electric furnaces are conductors of electricity.

I have illustrated my invention in the accompanying drawings, in which— 50 Figures 1 and 2 are, respectively, a horizontal and a vertical section of a furnace adapted to perform the functions of the present invention; Figs. 3 and 4, are, respectively, a horizontal and a vertical sec-

tion of a modified form of furnace; Fig. 55 5 is a vertical section of still another modified form of furnace; Figs. 6 and 7 are detail views illustrating parts of the furnace shown in Fig. 5; and Fig. 8 is a diagram of another modification. 60

In general, it may be stated that the figures are mainly diagrammatic, inasmuch as the invention relates to a broadly conceived invention wherein specific details are of comparative unimportance. 65

Referring to Figs. 1 and 2, the characters 1 indicates a pool of molten metal surrounded by a container, 10, which may be composed of the mixture from which the molten or fluid metal 1 is produced by the 70 action of the furnace. Around the pool 1, at a suitable distance therefrom, such that the temperature conditions do not interfere with the operation, is located a ring, 2, of laminated iron surrounded by a conducting 75 coil, 3, from which, at intervals of 120°, conductors 4 and 5, branch off and are connected to the collector rings, 7, 8 and 9, of a three-phase generator, or to the terminals 80 of a three-phase transformer. Fig. 3 illustrates the same general idea as applied to a resistance furnace in which the molten metal 1 is itself the resistance. The current for melting the metal is applied through terminals, 11, 11, which are supplied with 85 means for water cooling as shown at 12, 12. Within or without or underneath the ring 1 is arranged a ring 2 of laminated iron 90 surrounded by a coil 3, as before. In Figs. 3 and 4, the ring of laminated iron is shown 95 as being located within the ring 1 of molten metal.

In both the forms of furnace hereinbefore described it is possible to set up currents in molten metal which will cause a rotation of 95 the metal or a revolution thereof such as will produce the desired stirring of the metal while it is in a molten state. Such effects are produced by causing currents to flow through the rotary field constituted by 100 the laminated core, 2 and the conductor, 3. Taking Fig. 3 as an example, the molten metal being kept in circulation, no portion of it remains very long in close proximity to the electrodes, which is in itself an advantage in addition to the stirring action. Coming now to the Figs. 5, 6 and 7, we have 105 a similar arrangement in which, however,

the magnetic circuit is arranged underneath the fluid material and is depressed at intervals to receive coils, as shown at 3, which coils take the place of the continuous coils 5 shown in the earlier figures of the drawing. In connection with this furnace it may be remarked that it is novel to send current into a ring of fused metal so that the current splits into two parallel currents, one 10 in each half of the ring.

Referring to Fig. 8, this shows a conduction furnace in which the melted metal 1 is shown in a trough having the shape of a waved ring. The current induced in the 15 ring 1 by a transformer having an iron core, 15, and a primary core, 16. The ring 1 constitutes the secondary and the current induced within it maintains it in fusion. In addition to this transformer there is a 20 three-phase transformer to effect the rotation. This is a ring 2 of laminated iron surrounded by coils 3 and provided with terminals 4, 5 and 6, as explained in connection with the earlier figures of the drawing. 25

The directions of the eddy current in the fused metal 1, induced by the three-phase ring, are in general at right angles to the fusing current induced by the transformer 20 15—16, for which reason, the two do not interfere with each other.

It is obvious that in addition to the alternating current devices shown in the drawings, it is possible to produce a direct current

analogy in the form of a motor, the commutator brushes being represented by water cooled or infusible contacts projecting into the fused mass and serving to transmit therethrough a direct current, preferably of low voltage and extremely heavy amperage. If 40 this current be now cut by a constant magnetic field, the entire liquid will rotate or revolve.

In another application filed July 25, 1904, Serial Number 217,954, of which this application is a division, claims are made upon the apparatus described herein.

I claim as my invention:

1. The method of causing a circulation of conducting molten material in an electric 50 furnace which consists in inducing secondary currents within the body of the molten material and producing a rotating force upon the induced currents by subjecting them to the action of an alternating rotating 55 magnetic field.

2. The method of stirring highly heated, fused, conducting material, which consists in maintaining an alternating rotating magnetic field in inducing relation thereto. 60

Signed at New York, in the county of New York, and State of New York, this 30th day of June A. D. 1905.

HENRY NOEL POTTER.
